METHOD OF REFINING HYDROCARBON OIL

Bruno Kuno Engel, Hoglandstorget, and Fredrik Teodor Emanuel Palmqvist, Stockholm, Sweden, assignors to Aktiebolaget Separator-Nobel, Stockholm, Sweden, a corporation of Sweden

Application December 8, 1945, Serial No. 633,768

1 Claim. (Cl. 196—40)

1

This invention relates to a process for refining natural and thermally pretreated mineral oils and mineral oil products by the aid of acid refining agents such as sulphuric acid, chlorosulphonic acid, fluorosulphonic acid and others.

One object of the present invention is to provide a continuous refining process permitting the use of centrifugal separators fitted with only two liquid outlets. Further objects are to carry out the refining process with a minimum of acid refining agent and in such a manner that the raffinate is substantially free from acid compounds so that it does not require any treatment with alkali.

Other objects of the invention will appear from the following description.

It has previously been suggested that mineral oil and mineral oil products be continuously refined by introducing and mixing sulphuric acid into a stream of oil and to conduct the mixture, after a certain time of reaction, to a centrifugal separator in order to separate the refined oil from the acid and the undesirable hydrocarbons removed by the acid. In carrying out this process, however, certain difficulties have been experienced due to the formation, in the centrifuge bowl, of three different liquid phases, viz. oil, acid sludge and water-diluted free acid. So as to permit continuous discharge of these three liquid phases from the bowl, the latter has to be provided with three outlets. In practice it has proved difficult to adjust these outlets satisfactorily for continuous operation. Moreover, the dilute free acid often causes serious corrosion of the centrifuge bowl and receptacles.

We have discovered that when adding sulphuric acid or other acid refining agents to mineral oils, an extraction of the more unstable components of the oil takes place, as well as a reaction between these components and the acid. At this reaction water is formed which dilutes the acid and reduces its power of retaining the extracted hydrocarbons and reaction products in solution. As the reaction proceeds, these compounds therefore partly separate from the acid solution, forming so-called acid sludge, the before-mentioned three liquid phases thus being obtained. Part of the acid sludge is re-dissolved in the oil, thereby impairing the quality of the raffinate. The latter contains sulphonic acids and other undesirable compounds, necessitating an alkali wash to obtain a satisfactory quality of the raffinate.

By properly adjusting, according to the present invention, the temperature and the time of the acid treatment it has proved possible to extract,

2

in a preliminary step, the more unstable hydrocarbons and to remove by centrifugal separation the acid extract solution from the oil, before water yielding reactions take place to any substantial extent. Thus dilution of the acid by reaction water and the resulting formation of a third liquid phase is avoided, and in the centrifuge only two phases are separated, viz. oil and acid extract solution. The centrifuge bowl therefore has to be provided with two liquid outlets only, and the before-mentioned difficulties hitherto inherent with continuous operation are eliminated.

To ensure this, the contact time in the preliminary extraction step has to be relatively short, and generally it should not exceed 4 minutes. For the same reason, the temperature ought to be relatively low, mostly below 20° C. and in some cases chilling may have to be employed.

The amount of sulphuric acid or other acid refining agent should not be larger than required for the extraction, at the short contact time indicated above and with due regard to the mixing and contacting equipment used, of at least the major portion of the more unstable components of the oil—i. e. those olefinic, aromatic and hydro-aromatic substances, which react relatively rapidly with the sulphuric acid during formation of reaction water so that the majority of the non-paraffinic hydrocarbons remaining in the oil are relatively stable and can be subjected to a relatively prolonged action of sulphuric acid or other acid refining agent without any danger of substantially water yielding reactions taking place.

When the more unstable or reactive hydrocarbons have been removed from the oil by this preliminary treating step, the oil is further treated for extraction of the remaining, mainly non-paraffinic hydrocarbons to be removed. This main treatment can be carried out in one or several steps by the aid of known extraction equipment. A suitable method is to feed oil and acid refining agent into a mixer and conduct the mixture, after a certain time of contact, to a centrifugal separator, where the acid extract solution is removed from the oil. The latter may then once or several times again be mixed with acid refining agent and separated. Since water yielding reactions may not be feared in these extraction steps, only two liquid phases are always obtained, viz. oil and acid extract solution, and the centrifuge bowls can be provided with two outlets only.

It has proved possible to reduce the sulphuric acid consumption considerably by carrying out the extraction in counter-current, i. e. by mixing

acid extract from a later step with oil fed to a previous step. The content of extracted hydrocarbons in the acid extract is thereby gradually increased, and when the extraction is completed the extract can be subjected to a treatment for recovering the sulphuric acid and the extracted substances, respectively. This can be effected by adding water to the acid extract, thus splitting it into two phases, viz. on one hand dilute acid which may be concentrated e. g. by adding SO_3 , and on the other hand a mixture of extracted hydrocarbons. The latter may also be dissolved by a suitable selective solvent, whereby the acid is directly recovered in a concentrated state.

The accompanying drawing forms a part of the specification and shows diagrammatically a preferred and practical embodiment of the invention.

The oil to be refined is fed through a pipe 1 into a mixer 2 where it is mixed with a small proportion of acid refining agent, e. g. sulphuric acid, entering the mixer through a pipe 3 and/or 33. The quantity of acid used in this preliminary step amounts to maximum 30% of the total quantity of acid required, which varies according to the nature of the oil to be refined, the quality desired, the equipment used etc., between 1 and 20 parts—usually 5–12 parts—of acid being required for 100 parts of oil. The temperature in the mixer 2 is kept below 20° C. and the time of contact amounts to 1–4 minutes. Under these circumstances, an extraction of the more unstable components of the oil takes place, while water yielding reactions are substantially avoided. Thus only two phases are formed, viz. oil and an acid extract solution containing the unstable substances extracted from the oil.

From the mixer 2 the mixture is passed through a pipe 4 to a centrifuge 5 where the acid extract solution is separated from the oil and is discharged through a pipe 6 into a tank 7. Through a pipe 8 water is added to the extract solution, causing two phases to be formed, viz. one oil phase and one phase consisting of dilute sulphuric acid with sulphonic acids dissolved therein. The recovered oil is discharged through a pipe 9 and can be used as fuel oil whereas the sulphuric acid solution, being drawn off through a pipe 10, is usually a by-product of no value.

The pre-refined oil from the centrifuge 5 is passed through a piping 11 to a second mixer 12 where it is once more treated with sulphuric acid. Thence the mixture passes through a pipe 13 to a centrifuge 14 where the acid extract solution is separated from the oil and is discharged through a pipe 15. The oil is conducted through a pipe 16 to a third mixer 17 in which the acid treatment is repeated. The acid-oil mixture passes through a pipe 18 to a centrifuge 19, from which the separated oil is taken through a pipe 20 to a fourth mixer 21. Here the final acid treatment takes place and the mixture flows through a pipe 22 to a centrifuge 23, from which the raffinate is discharged through a pipe 24.

The sulphuric acid is preferably passed in counter-current to the oil, as shown in the drawing, so as to obtain the best possible refining with a minimum of acid, fresh acid being used only in the last step, where the oil contains only a small amount of soluble hydrocarbons. In carrying out the process in that manner, the acid extract solution discharged from the fourth centrifuge 23 is conducted through a pipe 25 to the third mixer 17, and from the third centrifuge 19 the acid extract solution is then taken through the pipe 26 to the

second mixer 12, to be finally discharged from the second centrifuge 14 through the pipe 15.

In continuous operation, the extract solution from the centrifuge 14 may be regenerated e. g. in a tank 27 in which the extract solution is treated with a solvent for the hydrocarbons, the solvent entering through a pipe 28. The hydrocarbon solution is drawn off through a pipe 29 and is taken to a distillation plant for recovering the solvent and the hydrocarbon extract, while the recovered concentrated acid is passed through a piping 30 and 31 to the last mixer 21. Fresh acid to make up for losses is supplied through a pipe 32.

15 The acid can also be recovered by adding water to the extract solution and concentrating the dilute acid thus obtained by means of SO_3 or evaporation.

From the pipe 15 the before-mentioned pipe 3 is branched off, part of the acid extract solution from the centrifuge 14 thus being conducted to the primary mixer 2 to extract the more unstable components of the oil. The mixer 2 is also connected, by means of the pipe 33, to the fresh acid supply pipe 32 so that fresh acid can be used when starting up the plant. However, as soon as acid extract solution discharges from the centrifuge 14, only such solution should preferably be supplied to the mixer 2. In certain cases it may be of advantage to supply both fresh acid and acid solution to the mixer 2.

When treating highly viscous oils it is advantageous to carry out the refining after addition of a diluent, which should preferably have a low viscosity and be of inert nature so that it is not attacked by the refining agent. The refining process can then take place at low temperature without excessive power consumption of the mixers and without undue reduction of the plant capacity and increase of the treating time, respectively. As an example of a suitable solvent may be mentioned light paraffinic hydrocarbons or hydrocarbon mixtures in such a proportion—preferably not more than 25%—that the viscosity of the mixture does not exceed 75 centistokes. The diluent can be recovered by means of distillation.

By the described process several advantages are obtained:

50 Only the relatively small amount of acid used in the preliminary treating step is obtained as a by-product of no value, whereas the acid used in the subsequent steps acts only as a solvent and can be substantially regenerated, which means a considerable saving of acid.

The formation of reaction water and the resulting splitting-up of the extract solution into acid sludge and free dilute acid is substantially avoided before and during the separation of the extract solution from the oil. The centrifugal separators used can thus be designed for separating two phases only, and the absence of reaction water reduces the corrosive action of the acid on the centrifuge bowls.

60 Reaction products, such as sulphonic acids etc., are not formed at all or are formed only to a negligible extent prior to or during the separation. Consequently, the danger of such undesirable products being re-dissolved in the pre-refined oil is eliminated or reduced so that the raffinate need not be treated with alkali but has only to be subjected to a bleaching process.

65 On account of the short contact time, the treating tanks can be relatively small and the

amount of oil tied up in the process is reduced accordingly.

As compared with the acid treating processes hitherto known, which do not involve any preliminary extraction of the more unstable components of the oil, the process according to the present invention insures either a better raffinate quality at the same yield, or a higher yield of raffinate with the same quality.

What we claim is:

The process of refining mineral oils and mineral oil products, which comprises continuously introducing, in a primary treating step, fresh and concentrated sulphuric acid into a stream of oil to be refined, and in which primary treating step the acid is caused to act upon the oil at a temperature not exceeding 20° C. and during a period not exceeding four minutes, whereby by means of acid only the more unstable components of the oil are dissolved, while substantially inhibiting water yielding reactions by the same, passing the oil and acid mixture through a locus of centrifugal force to separate the mixture into two phases, one of which is a pre-refined oil product whereas the other is an acid solution of said more unstable components of the oil, and subjecting said pre-

refined oil to a further treatment comprising a plurality of steps each of which involves addition of an acid refining agent and in which the acid refining agent is caused to act upon the oil in counter-current thereto, each counter-current step involving centrifugal separation of the mixture into a refined oil product and an acid solution containing the less unstable soluble components of the oil.
